United States Patent Office

Des. 187,845
Patented May 3, 1960

187,845

SPOUT OR SIMILAR ARTICLE

Herbert V. Kohler, Kohler, Wis., assignor to Kohler Co.,
Kohler, Wis., a corporation of Wisconsin

Application January 9, 1959, Serial No. 54,113

Term of patent 14 years

(Cl. D91—3)

Fig. 1

Fig. 2

Fig. 3

Fig. 4 Fig. 5

Fig. 1 is a perspective view of a spout, showing my new design;

Fig. 2 is a side elevational view of the same;

Fig. 3 is a top plan view of the spout;

Fig. 4 is a front elevational view thereof; and

Fig. 5 is a rear elevational view of the spout.

Figs. 2-5 are on a slightly larger scale than Fig. 1.

I claim:

The ornamental design for a spout or similar article, as shown and described.
